APPARATUS FOR MAKING PAPER PULP

Filed March 30, 1923

4 Sheets-Sheet 2

<img alt="A detailed cross-sectional diagram of a mechanical device, likely a clutch or gear assembly, showing four main circular components labeled 62, each with internal parts 61 and 65. The components are interconnected by various shafts, bearings, and a central spring mechanism labeled 73. Labels include 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2019, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, 2060, 2061, 2062, 2063, 2064, 2065, 2066, 2067, 2068, 2069, 2069, 2070, 2071, 2072, 2073, 2074, 2075, 2076, 2077, 2078, 2079, 2079, 2080, 2081, 2082, 2083, 2084, 2085, 2086, 2087, 2088, 2089, 2089, 2090, 2091, 2092, 2093, 2094, 2095, 2096, 2097, 2098, 2099, 2099, 2100, 2101, 2102, 2103, 2104, 2105, 2106, 2107, 2108, 2109, 2109, 2110, 2111, 2112, 2113, 2114, 2115, 2116, 2117, 2118, 2119, 2119, 2120, 2121, 2122, 2123, 2124, 2125, 2126, 2127, 2128, 2129, 2129, 2130, 2131, 2132, 2133, 2134, 2135, 2136, 2137, 2138, 2139, 2139, 2140, 2141, 2142, 2143, 2144, 2145

UNITED STATES PATENT OFFICE.

WILLIAM S. LOWE, OF CHICAGO, ILLINOIS.

APPARATUS FOR MAKING PAPER PULP.

Application filed March 30, 1923. Serial No. 628,689.

This invention relates to a new and improved method of making paper pulp and an apparatus adapted for carrying out such method. More specifically, the method and apparatus relate to the cutting of the pulp wood into the short fibres necessary for use in paper making.

As is well known in the art in making paper such as used for newspapers, a certain small proportion of the pulp is commonly formed by chemical processes which gives a pulp of comparatively long fibre. The greater portion of the pulp, however, is commonly formed not by cutting but by grinding by pressing the ends of the logs against a grindstone revolving at a high speed. The grindstone and the contacting face of the log are kept covered with water to keep down the heat and the pulp is formed in the wet state. The excess water runs off and carries with it a certain percentage of the pulp which may approximate ten percent, which portion of the pulp is lost.

The operation of this method requires very considerable power and is comparatively slow. A grinder of this type requires approximately fifty horsepower to produce a ton of pulp. This high power requirement renders pulp making prohibitive unless cheap water power is available. It also is a somewhat seasonal operation since it can only be carried on to full extent at periods during high water when maximum power is available.

A further objection to this pulp lies in the fact that the pulp is formed wet and when shipped wet, the weight of the water very materially increases the cost of freight.

The present machine is also adapted for making pulp from leather waste, this pulp being used in the formation of leather board and similar material.

The formation of pulp from leather scrap is, by methods now in use, a very expensive process since it requires a very large expenditure of power. With the apparatus now used it requires from eighteen to twenty-four hours to reduce leather scraps to pulp and a 1,000 pound beater will require about 100 horsepower to turn it when operating upon leather scraps. Consequently, this op-

eration can only be carried on where cheap power is available.

It is an object of the present invention to provide a new and improved apparatus and method adapted for the formation of pulp from wood, leather or other similar material.

It is a further object to provide means and method of this character wherein the production is carried on by a cutting rather than a grinding action and which is adapted for rapid and efficient operation with a very low power expenditure.

It is an additional object to provide a construction adapted to produce pulp in the dry state.

It is another object to provide an apparatus whereby the pulp produced may be readily handled by mechanical means.

Other and further objects will appear as the description proceeds.

I have illustrated certain preferred embodiments of my invention in the accompanying drawings in which:

Figure 1 is a vertical section showing one form of apparatus;

Figure 2 is a plan view of the apparatus shown in Figure 1;

Figure 3 is a fragmentary section showing the feed drive mechanism;

Figure 4 is a fragmentary section showing the knife mounting;

Figure 5 is a view similar to Figure 1 showing a modified form of construction;

Figure 6 is a horizontal section of the form of construction shown in Figure 5 taken on line 6-6; and

Figure 7 is a fragmentary plan view showing the location of the knives in the form of construction shown in Figures 5 and 6.

Referring first to the form of construction shown in Figures 1 to 4, the base member 11 is supported from the floor by legs 12 and by the leg 13 which latter is provided with a bearing for the drive shaft 14. The drive shaft 14 is driven by means of power supplied to the pulley 15. As shown in Figure 3, the bevel-gear 16 is keyed to the inner end of shaft 14 and the thrust bearing 17 is located between bevel-gear 16 and the fixed bearing 18.

The shaft 14 carries the pinion 19 meshing with pinion 20 carried upon the feed drive shaft 21. The feed drive shaft is supported in bearings 22, 23 and 24. This shaft 5 is provided with the worm gear 25 which fits between bearings 23 and 24, and which meshes with the gear 26 carried by the vertical feed drive shaft 27.

The bevel-gear 16, carried by the main 19 drive shaft, meshes with the bevel-gear 28 which latter is secured by key 29 to the main drive sleeve 30.

The cutter-disk 31 is secured to the sleeve 30 by key 32 and rotates therewith. The 15 bearing collar 33 is secured to the upper end of the main drive sleeve 30 by means of a set screw 34. This collar 33 rests upon the ball-bearing 35, which latter rests upon a seat 36 formed upon the upper surface of 20 the base plate 37. The plate 37 is secured to the base member 11 by means of bolts 38.

The cutter-disk 31 is provided with a plurality of radial openings 39, as best shown in Figure 4. These openings 39 are under 25 cut at 40 to facilitate discharge of the cut material. The knives 41 are secured to the opposite face of the openings 39 by means of clamp members 42 held in place by screws 43. The clamps 42 are provided with the 30 upwardly extending edge portions 44 through which pass adjusting screws 45. The upper ends of these screws 45 bear against the lower edges of the knives 41 and the latter may be adjusted by rotation of 35 these screws.

The disk 31 is provided upon its lower central portion with the overhanging flange 46 which encloses an upwardly extending flange 47 carried by the base of the pulp 40 receiving chamber 48. This chamber 48 is formed of sheet metal and is secured to the base plate 37. The chamber 48 is provided with the outlet 49 and with the clean-out door 50 which latter is held in closed position by catch 51.

The guide cylinders 52 are secured in spaced openings in the plate 37, being retained in place by screws 53. As shown in Figure 2, the apparatus selected for illustration comprises five such members 52 equally spaced about the axis of the cutter-disk 31. The upper ends of the members 52 are connected by the fixed spider 54 which is secured to the members 52 by bolts 55.

The vertical feed shaft 27 extends through the spider 54 and its upper end 56 is threaded. The thrust collar 57 is secured to the shaft 27 by set screw 58, and bears against the lower face of the central boss of spider 54.

The movable spider 59 is fitted upon the shaft 27 and is provided with arms 60 extending over the center of each of the guide cylinders 52. The presser rods 61 are carried 65 in the arms 60 and extend down into the cyl-

inders. The lower ends of the rods 61 are threaded and have secured thereto the presser disks 62. These disks are held in place by the lock nuts 63 and are provided with the pointed studs 64. The pins 65 extend 70 through the rod 61 above the spider arm 60 and limit downward movement of the presser rods. The collars 66 are secured to the rods 61 below the spider by means of set screws 67 and the springs 68 are carried 75 by the rods between the collars 66 and spider arms 60.

The spider 59 fits loosely on shaft 27 and does not engage the threads of the shaft. The actuating arm 69 is pivotally secured to 80 the spider 59 by means of screw 70. The free end of this arm 69 is provided with a threaded portion engaging the threaded portion of the vertical feed drive shaft 56. This end of the arm is urged into engagement with the threaded portion 56 by the spring 96. The disconnecting arm 71 is pivoted to spider 59 upon screw 72. This arm 71 engages the cam portion 73 of the arm 69. The upper end of the arm 71 has secured 85 to thereto the operating cord 73 which, as shown, passes over pulleys 74 and 75.

The guide rod 76 is supported at its lower end upon extension 77 formed upon the fixed spider 54 and is held in place by lock nuts 95 78 and 79. This guide rod passes through extension 80 formed on the upper spider 59 and the engagement of the rod with the spider prevents rotation of the latter and guides it in its vertical movement.

The water header 99 encircles the guide cylinders 52 and is provided with the discharge pipes 100, one of which enters each guide cylinder. Water may be admitted into the header 99 from pipe 101 controlled by 105 valve 102.

The form of construction shown in Figures 5 to 7 is in many ways similar to that just described. The main drive shaft and its gears, and the horizontal feed drive shaft 110 and its gears are identical in the two cases. All parts which are identical in this second form of the device with similar parts in the first form have been given the same reference characters in both forms.

The main drive sleeve 81 has secured thereto by key 83 the bevel-gear 82 meshing with the bevel-gear 16. Immediately above this gear the gear 84 is secured to sleeve 81 by key 85. Located around the gear 84 and meshing with it are five gears 86. These gears 86 are carried upon the vertical shafts 87 supported in frame 88. Above the gear 86 upon each shaft is secured the cutter-carrying cone 89. These cones are provided upon their upper surface with the conical chamber 90. As shown in Figure 7, this chamber 90 is provided with a substantially diametric opening 91 upon the under portion of which are secured the knives 92 125 130

and 93. These knives are faced in opposite directions and may be secured and adjusted in a manner similar to the knives 41 of the first form of the device.

5 In the second form of the device the pulp-receiving chamber 94 is formed of sheet metal and secured to the base plate and supporting frame in a manner similar to the first form. This chamber is provided with 10 the outlet 95. In this form of construction, 15 guide flanges 97 are formed upon the inner faces of the guide cylinders 52, these flanges fitting in notches 98 formed in the presser members 62. This interengagement prevents 20 rotation of the presser head and by means of the pointed studs 64 rotation of the stick or log is prevented. It will be understood that the logs or sticks used will not be greater in diameter than the clearance between the opposite flanges 97.

In the operation of the first form of apparatus, the power is supplied to pulley 15, carried upon shaft 14, and by means of bevel-gears 16 and 28, power is transmitted to the 25 main drive sleeve 30. This drive sleeve carries the cutter-disk 31 and the knives 41 are rotated rapidly with the disk. The logs or sticks of material to be reduced to pulp are placed in the guide cylinders 52 and 30 their lower faces are engaged by the upper face of the cutter-disk and by the knives. The movable spider 59 is lifted in order to insert the logs, the spider carrying with it the presser rods 61 and the presser disks 62.

35 The spider 59 is connected to the vertical feed drive shaft 27 by means of the threads cut in the face of the actuating arm 69. The spider is lifted by means of the cord 73 passing over pulleys 74 and 75. This upward pull causes the upper end of the arm 69. By means of this engagement the arm 69 is thrust against the spring 96 and the threads are moved out of engagement with 40 the threaded portion 56 of the shaft 27. The spider and its attached presser disks and rods are then raised by the pull upon the cord 73. The guide rod 76, by its engagement with the extension 80, prevents rotation 45 of the spider 59 and causes it to move directly upward, the rod 61 and presser disk being maintained in alignment with their respective guide cylinders.

50 When the logs have been placed in the cylinders, the movable spider 59 is lowered until the presser disks engage the upper faces of the logs. The pressure upon the logs is governed by springs 68 which also permit the disks to be properly seated upon the 55 logs although there may be some variation in the lengths of logs. The studs 64 are pressed into the ends of the logs and hold the presser disks in fixed relation to the logs.

55 The vertical feed shaft 27 is rotated by means of power supplied through the pinion

19 carried upon the shaft 14. This pinion meshes with pinion 20 on the feed drive shaft 21 and serves to drive the latter shaft. The worm gear 25 upon the feed drive shaft 21 meshes with the gear 26 upon the vertical feed drive shaft and causes the latter to rotate.

It will be seen that there is a very considerable gear reduction through the pinions 19 and 20 and the worm gears 25 and 26. 75 Consequently, the feed drive shaft is rotated at relatively low speed. Further, the threads upon the portion 56 of the shaft 27, which engage the threads of member 69 carried by the spider 60, may be made upon a 80 relatively small pitch. It may be desirable, when operating upon different woods or materials of differing hardness, to vary the feed drive by substituting gears of differing ratios for pinions 19 and 20. It will be apparent, however, that the speed of rotation of the disk 31, and consequently the cutting speed must bear a definite ratio to the rate of feed downwardly of the logs.

The logs are thus automatically fed down 90 against the cutter disk 31 and consequently against the knives 41. These knives may be adjusted so as to vary the depth of the cut. The depth of the cut will determine the length of the fibre secured and it may also be 95 found desirable to vary the depth of the cut somewhat according to the hardness of the material operated upon.

The material cut or shaved from the ends 100 of the logs drops into the pulp receiving chamber 48 and it is drawn by suction from this chamber through the outlet 49. The chamber is closed and the air drawn out of the pulp will be drawn down through the 105 guide cylinders 52 and across the face of the cutter plate. This current of air will serve to cool the cutting faces and prevent overheating and burning. Under some circumstances, in order to provide a moist or wet pulp or to reduce heating, it may be desirable to introduce water upon the logs or sticks and upon the operating knives. This may be done by means of the header 99 and pipes 100 which serve to lead the water to 110 each guide cylinder and stick.

115 The operation of the second form of apparatus shown is in many ways identical with that just described. The feed mechanism is exactly similar. In this form of apparatus, however, there is a separate cutting means for each log or piece of material. The cutter carrying cones 89 are driven from the sleeve 81 by engagement between the gear 84 and the gears 86. These cutter cones rotate about the axes of the material introduced. Each cone is provided with a pair of knives and these knives are located upon an angle so that the cut taken is not squarely across the 125 face of the material operated upon, as in the first form, but is a conical shaving or 130

cut from its end. In this way where the material is provided with longitudinal fibres such as are present in wood, a cut of any specified depth will produce fibres of greater length than will be produced by a cut of the same depth squarely across the end of the log.

This latter form of the device is particularly adapted for use in formation of pulp from leather scrap. Leather scrap would be impregnated with some binder such as silicate of soda and would be pressed into shape to form cylindrical bodies of approximately the size of the logs which the machine is adapted to receive when working upon wood. These pressed bodies of leather scrap are reduced to pulp by the cutting action of the knives. The binder may be later removed by a beating and washing operation.

In both forms of machine the rotating cutting holding members have a beating action upon the shaved off material passing through the openings adjacent the cutting knives. This action is of value in thoroughly disintegrating the shaved off thin layer of material.

The forms of apparatus shown are capable of producing pulp from wood with a comparatively small power expenditure and much less than that required by any grinding process. The use of my process and apparatus will thus render available much cheap pulp wood which has heretofore not been used due to the lack of cheap power which is essential in making pulp by the old grinding processes which require a large amount of power.

The two forms of apparatus shown are illustrative only of the apparatus covered by

my invention and may be modified to meet varying conditions within the scope of the appended claims.

I claim:

1. Apparatus for pulp production comprising a revolving member having a cone-shaped seat adapted to engage the end of a stick of fibrous material, a plurality of radially extending, spaced knives carried by said member adapted to cut successive layers of fibrous material from said stick, and a guide cylinder located parallel to the axis of rotation of the member and adapted to guide the stick into engagement with the member.

2. Apparatus for pulp production comprising a revolving member having a cone-shaped seat adapted to engage the end of a stick of fibrous material, a plurality of radially extending, spaced knives carried by said member adapted to cut successive layers of fibrous material from said stick, a guide cylinder located parallel to the axis of rotation of the member and adapted to guide the stick into engagement with the member, and a follower adapted to press the stick into engagement with the member.

3. Apparatus for pulp production comprising means adapted to cut successive thin conical layers from the end of a stick of fibrous material, a guide cylinder adapted to direct the stick of material against the cutting means, a follower adapted to carry the stick against the cutting means, driving means for said follower, and means adapted to disconnect the follower from the driving means.

Signed at Chicago, Illinois, this 28th day of March, 1923.

WILLIAM S. LOWE.
